UNITED STATES PATENT OFFICE.

GEORGE GOEBEL, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

MACHINE FOR FEEDING CROWNS AND THE LIKE.

Original application filed August 28, 1919, Serial No. 319,932. Divided and this application filed December 28, 1920. Serial No. 433,965.

To all whom it may concern:

Be it known that I, GEORGE GOEBEL, a citizen of the United States, residing at Baltimore and State of Maryland, have invented 5 certain new and useful Improvements in Machines for Feeding Crowns and the like, fully described and represented in the following specification and the accompanying drawings, forming a part of the same.

10 This invention relates to improvements in machines for feeding crowns and the like. The present application is a division of an application filed August 26, 1919, Serial No. 319,932.

15 It is the principal object of the invention to provide apparatus of the type mentioned, capable of efficiently feeding crowns and the like at a high rate of speed.

With this general object in view the invention consists in the combinations, details 20 of construction and arrangements of parts which will first be described in connection with the accompanying drawing and then more particularly pointed out.

25 In the drawing—

Fig. 1 is a view in vertical section of an apparatus constructed in accordance with the invention taken on a broken line passing through the selecting and feeding mechanisms and the chute connection;

30 Fig. 2 is a view in elevation, with parts removed of part of the crown feed;

Fig. 3 is a sectional view taken on the line 3—3 of Fig. 2;

35 Fig. 4 is a similar view taken on the line 4—4 of Fig. 2;

Fig. 5 is a detail view in vertical section of a portion of the hopper and associated parts.

Referring to the drawings, closures such 40 as crowns are selected from a mass, the mass being contained, for example, in a hopper. As here shown, crowns are delivered to a hopper 15 having a slanting bottom 16 and a partial partition 17 so that the crowns 45 move toward the back and bottom of the hopper. The hopper is shown as bolted or otherwise secured to an upright 18 supported in any suitable manner.

Selecting means is provided for delivering 50 the crowns uniformly faced. Although capable of various constructions, in that here shown as an example, the hopper body is open at the back and forming a back en-

closure therefor is a rotating plate 20 mounted on a shaft 21 journalled in a bearing 55 bracket 22 suspended from the hopper. Shaft 21 is rotated by a pulley 23 connected by a belt 24 with a second pulley 25 driven by a shaft 26. Mounted on this latter, to rotate the same, is a worm gear 27 meshing 60 with a worm wheel 28 on a vertical shaft 29 to which power may be applied in any suitable manner.

Between the hopper body and its back plate 20 is a space which may be called a 65 separator way. This separator way includes a primary channel 35 and a secondary channel 35^a. These channels, in the present embodiment, are formed by the hopper and back plate as follows: The hopper has, at 70 the back, an annular rim or face 36 terminating in an abrupt ledge or shelf 36^a, beyond which is an outwardly inclined surface 37. As appears in Fig. 1, the bottom portion of the shelf 36^a and surface 37 are formed by a 75 separate extension 37^a bolted to the hopper, but this is for convenience of manufacture, and the extension piece may be considered as part of the hopper body. The back plate 20 has a face portion 38 so disposed with 80 relation to the face 36 of the hopper that the intervening space permits the passage of crowns in single edgewise position but not in diskwise position or in dual edgewise relation. Extending outwardly to substantially parallel the surface 37, the plate 20 has an inclined rim 39. At the bottom, the rim of the secondary channel 35^a is cut away 85 to provide a hopper delivery mouth herein- 90 after referred to.

Crowns sliding down the lower part of the hopper enter the primary channel 35 of the separator way where they take an upright position indiscriminately faced. In the case of inwardly faced crowns, the skirts 95 lodge on the ledge 36^a as appears in Figs. 1 and 4, and the crowns are arrested thereby. Outwardly faced crowns, however, slide past the ledge without being arrested and enter the secondary channel 35^a. Here they eventually reach the delivery mouth through 100 which they pass out.

To elevate the crowns in the separator way, at a plurality of locations in the rotating plate 20 there are provided spring 105 pressed studs 40 which extend into the pri-

mary channel. As the back plate rotates, the arrested crowns in the primary channel are carried around the separator way until they reach a point where they can drop back 5 into the mass. Thus, only properly faced crowns can reach the delivery mouth of the hopper.

The invention in its entirety includes in connection with the crown selecting means, 10 crown delivery means capable of delivering a plurality of crowns simultaneously and a magazine for receiving the delivered crowns. With the type of hopper and selecting means here shown, this delivery means may conveniently be a hopper mouth of a capacity 15 to deliver several crowns simultaneously. Although capable of various constructions, as shown, opening downwardly from the secondary channel of the separator way is 20 a delivery mouth formed by cutting away the channel rim. In the present instance, this hopper delivery mouth is represented by the space between the points 41, 42 and has a capacity of four crowns. That is to say, 25 any number of crowns, up to and including four may simultaneously pass out from the hopper separator way.

Below the delivery mouth is a magazine for receiving the delivered crowns. As 30 shown, the extension part 37^a which provides the inclined surface 37 of the separator way is extended downwardly to form a back wall 43 for the magazine. At the bottom of this wall is a thickened portion providing a 35 magazine bottom 44. The magazine is provided with cover plates 45 separated slightly as appears in Figs. 4 and 5, to provide a view of and access to the crowns in the magazine. It will be seen from the drawings 40 that the surface 37 of the separator way and the wall 43 of the magazine form a continuous supporting surface down which the crowns slide until they rest on the bottom ledge 44 in a horizontal row in upright 45 edge-to-edge relation.

The invention in its entirety includes crown conducting means leading away from the magazine and such means may take the form of a gravity-feed chute. In the present embodiment, at one end of the magazine, the bottom rib 44 (Fig. 2) curves sharply 50 downward to join a gravity feed chute 46, more fully described hereinafter. Opposite this end of the rib 44 is a block 47 secured 55 to the plate 37^a, which forms an end wall for the magazine and which has a curved edge, as appears in Fig. 2, serving to aid in guiding the crowns into the chute.

Means is provided for causing the crowns 60 in the magazine to move into the chute. This may be accomplished, as an example, by a pusher reciprocating through the magazine to push the row of collected crowns into the chute. Although capable of various 65 constructions, as here shown, slidible

through the magazine is a pusher 48 of the form shown in Figs. 2-4. This pusher is supported, by means of an integral arm 49, from a slide block 50, the arm 49 passing through a suitable slot formed in the back 70 wall of the magazine. The top and bottom of the slide block 50 are rabbeted, as shown in Fig. 4. The top slides on a lug 51 formed on the back plate 43 and the bottom slides on a track member 52 suspended by 75 bolts 53.

The slide block 50 is driven in a manner to permit the pusher to yield in case a jam of crowns occurs. To this end, inserted in the slide block to swivel therein is a tubular 80 connecting member 54, held in place by a flange 55 and a collar 56, the collar being pinned to member 54 by pin 57. Passing through collar 56 and the connecting member 54, is a driving rod 58, squared at that 85 portion which passes through member 54 (Fig. 4). This driving rod is mounted on the pin 59 of a crank 60 rotated by shaft 26.

To yieldably connect the driving rod with the slide block 50, the rod is frictionally 90 held to the connecting member 54. To this end, the squared portion of rod 58 is embraced between a plug 61, held in place by pin 57, and a spring pressed block 62 slideable in the tubular connecting member 54. 95 Under normal conditions, as the rod reciprocates the friction of the parts described causes the slide block 50 to move with the driving rod, thus reciprocating the pusher in the magazine. In case, however, the 100 pusher encounters an excessive resistance, as in the case of a jam of crowns, the friction mentioned is overcome, thus permitting the driving rod to slide through connecting member 54 without moving the latter. As a 105 result, the pusher remains idle until the obstruction is removed.

To prevent the crowns from buckling upwardly as they approach the chute, yieldable guiding means is provided. As shown 110 in the present exemplification, mounted on a pin 63 is a ring 64 normally held in position by a leaf spring 65. This ring is positioned to guide the crowns downwardly into the chute and it can yield by moving on the 115 pin against its spring.

With the construction described, the pusher being withdrawn, crowns up to four in number drop into the magazine and are collected by the bottom rib 44. The rotation of 120 shaft 26 causes the pusher 48 to advance through the magazine, thus pushing the collected crowns toward the chute into which they drop, guided by end plate 47 and ring 64. By the time the rotation of shaft 26 has 125 withdrawn the pusher, another lot of crowns has accumulated for delivery and the operation continues. This construction makes possible an effective and rapid feed of the crowns.

As will be apparent from the drawings (Figs. 1 and 4, for example) the chute 46 is positioned at an angle to the vertical. In order to deliver only proper crowns, there is 5 provided a discharge opening in the chute and means for conducting proper crowns past such opening. Although capable of various constructions, in the present embodiment, the top part of the chute body is 10 formed by downward extensions from the back wall 43 and the end piece 47 of the magazine. Set into the rabbeted ends of these extensions (Fig. 1) is a plate 66 forming a part of the chute floor in alignment with the 15 floor 67 of the chute proper, but separated therefrom by a space 68. Considering the chute as a whole, this space 68 is a discharge opening formed in the floor of the chute. To conduct proper crowns past the discharge 20 opening, along each side of the opening is a ledge or guide rail 69. These ledges are so spaced as to serve as bearing surfaces for the skirts of proper crowns, but the space between them cannot be spanned by a defective 25 crown, such as one with a bent or defective skirt. With this construction, therefore, defective crowns upon reaching the opening 68 will, by gravity, drop out of the chute and may be collected as desired. Proper 30 crowns, however, being able to span the space between the ledges 69, will pass the discharge opening and slide down the chute.

It will be understood that the apparatus described is available for feeding complete 35 crowns to a capping head or crown shells to an assembling apparatus.

What is claimed is:

1. In apparatus for feeding crowns and the like, and in combination a hopper having a delivery mouth of a capacity to deliver 40 a plurality of crowns simultaneously, means associated with the hopper for causing the crowns delivered to said mouth to be faced all one way, a magazine for receiving the delivered crowns, a gravity-feed chute leading from the magazine, and means for causing the crowns in the magazine to move 45 into said chute.

2. In apparatus for feeding crowns and the like, and in combination a hopper having a delivery mouth of a capacity to deliver 50 a plurality of crowns simultaneously, means associated with the hopper for causing the crowns delivered to said mouth to be faced all one way, a magazine for receiving the delivered crowns, a gravity-feed chute leading from the magazine, and a 55 pusher for pushing the crowns in the magazine into said chute.

3. In apparatus for feeding crowns and the like, and in combination a hopper having a delivery mouth of a capacity to deliver 60 a plurality of crowns simultaneously, means associated with the hopper for causing the crowns delivered to said mouth to

be faced all one way, a magazine for receiving the delivered crowns, a gravity-feed chute leading from one end of said magazine, and a pusher reciprocating through the magazine to push the collected crowns into 70 said chute.

4. In apparatus for feeding crowns and the like, and in combination a hopper having a delivery mouth of a capacity to deliver 75 a plurality of crowns simultaneously, means associated with the hopper for causing the crowns delivered to said mouth to be faced all one way, a magazine for receiving the delivered crowns, a gravity-feed chute leading from the magazine and a yieldably 80 driven pusher for pushing the crowns in the magazine into said chute.

5. In apparatus for feeding crowns and the like, and in combination a hopper having a delivery mouth of a capacity to deliver 85 a plurality of crowns simultaneously, means associated with the hopper for causing the crowns delivered to said mouth to be faced all one way, a magazine for receiving the delivered crowns, a gravity-feed chute leading from the magazine, a pusher for 90 pushing the crowns toward said chute, and guiding means for directing the movement of the crowns.

6. In apparatus for feeding crowns and the like, and in combination a hopper having a delivery mouth of a capacity to deliver 95 a plurality of crowns simultaneously, means associated with the hopper for causing the crowns delivered to said mouth to be faced all one way, a magazine for receiving the delivered crowns, a gravity-feed chute leading from the magazine, a pusher for 100 pushing the crowns toward said chute, and a yieldable guiding member located 105 above the path of the crowns for directing their movement.

7. In apparatus for feeding crowns and the like, and in combination, a hopper having a delivery mouth of a capacity to deliver 110 a plurality of crowns simultaneously, means associated with the hopper for causing the crowns delivered to said mouth to be faced all one way, a magazine for receiving the delivered crowns comprising a slanting back wall and a crown-holding bottom ledge, said magazine communicating with the hopper mouth, a chute beyond the end of said ledge for conducting crowns away from the magazine, a block beyond the chute 115 forming an end wall for the magazine, a pusher reciprocable through the magazine for pushing the received crowns into the chute, an arm on the pusher extending through a slot in the back wall of the magazine, a slide block supporting said arm, and means for reciprocating the slide block to reciprocate the pusher.

8. In apparatus for feeding crowns and the like, and in combination, a hopper for 120

- containing a mass of crowns, a magazine for receiving a plurality of selected crowns, a gravity feed chute leading from the magazine, means for selecting crowns from the mass in the hopper and delivering simultaneously a plurality of selected crowns, faced all one way, to the magazine, and a pusher for pushing the crowns in the magazine into said chute.
9. In apparatus for feeding crowns and the like, and in combination, a hopper for containing a mass of crowns, a magazine for receiving horizontal row of crowns in upright edge-to-edge relation, a gravity feed chute leading from the magazine adjacent one end thereof, means for selecting crowns from the mass in the hopper and delivering simultaneously a plurality of selected crowns, faced all one way, to the magazine, and a pusher for pushing the crowns in the magazine into said chute.
10. In apparatus for feeding crowns and the like, and in combination, a hopper for containing a mass of crowns, a magazine for receiving a plurality of selected crowns and having an exit opening, means for selecting crowns from the mass in the hopper and delivering simultaneously a plurality of selected crowns, faced all one way, to the magazine, and a pusher for pushing the crowns in the magazine to said exit opening, thereby to remove the crowns from the magazine.
11. In apparatus for feeding crowns and the like, and in combination, a magazine for receiving a longitudinal row of crowns in upright, edge-to-edge relation, a gravity feed chute adjacent one end of the magazine and communicating therewith, means for delivering crowns to the magazine all faced one way, and a pusher for pushing the crowns in the magazine into said chute.
12. In apparatus for feeding crowns and the like, and in combination, a magazine for receiving a longitudinal row of crowns in upright, edge-to-edge relation, a gravity-feeding chute leading away from said magazine adjacent one end thereof, crown delivery means adjacent the top of the magazine having a capacity for delivering simultaneously a plurality of crowns to the magazine, a pusher movable through the magazine for pushing the crowns in the magazine into the chute, and means for reciprocating the pusher.
13. In apparatus for feeding crowns and the like, and in combination, a magazine for receiving a row of crowns and having an exit opening for the crowns adjacent one end thereof, crown delivery means for delivering crowns faced all one way to the magazine and having a capacity for delivering a plurality of crowns simultaneously, and a pusher for pushing the crowns received by the magazine out of the same.
14. In apparatus for feeding crowns and the like, and in combination, a magazine for receiving a horizontal row of crowns in upright, edge-to-edge relation and having an exit opening for the crowns adjacent one end thereof, crown feeding means for feeding crowns faced all one way to the magazine and having a capacity for delivering a plurality of crowns simultaneously, and a pusher for pushing the crowns received by the magazine out of the same.
15. In apparatus for feeding crowns and the like, and in combination, a magazine for receiving a longitudinal row of crowns in upright edge-to-edge relation and having an exit opening for the crowns, crown delivery means for delivering crowns faced all one way to the magazine and having a capacity for delivering a plurality of crowns simultaneously, and a yieldably driven pusher for pushing the crowns in the magazine to said exit opening.
16. In apparatus for feeding crowns and the like, and in combination, a magazine for receiving a longitudinal row of crowns in upright edge-to-edge relation and having an exit opening for the crowns, crown delivery means adjacent the top of the magazine having a capacity for delivering a plurality of crowns simultaneously to the magazine, a gravity feed chute leading away from the magazine, adjacent one end thereof, and a yieldably driven pusher for pushing the crowns in the magazine to said chute.
17. In apparatus for feeding crowns and the like, and in combination, a magazine for receiving a horizontal row of crowns in upright edge-to-edge relation and having an exit opening for the crowns, crown delivery means for delivering crowns faced all one way to the magazine and having a capacity for delivering a plurality of crowns simultaneously, a pusher movable through the magazine to push the crowns to said opening thereby to remove the crowns from the magazine, a positively operated driving element, and a yieldable connection between said driving element and the pusher.
18. In apparatus for feeding crowns and the like, and in combination, a magazine for receiving a horizontal row of crowns in edge-to-edge relation, said magazine having an exit opening for the crowns, a pusher movable through the magazine to push the crowns to said opening, thereby to remove the crowns from the magazine, a reciprocable slide block with which the pusher is connected, a tubular connecting member mounted in the slide block, a driving rod passing through the connecting member and slidably therein, means for reciprocating the driving rod, and yieldable means for normally causing the connecting member to move with the driving rod.
19. In apparatus for feeding crowns and

the like, and in combination, a magazine for receiving a horizontal row of crowns in edge-to-edge relation, said magazine having an exit opening for the crowns, a pusher movable through the magazine to push the crowns to said opening, thereby to remove the crowns from the magazine, a reciprocable slide block with which the pusher is connected, a tubular connecting member mounted in the slide block, a driving rod having a squared portion, passing through the connecting member and slidable therein, means for reciprocating the driving rod, and a spring-pressed block within the connecting member and engaging the squared portion of the driving rod, whereby the connecting member and slide block are normally caused to be moved by the driving rod but may yield with relation thereto.

In testimony whereof, I have hereunto set my hand.

GEORGE GOEBEL.
